SIGN STAND FOR DISPLAYING POSTERS

Herman Green, Garden City, N. Y., assignor to
 City Tank Corporation, Corona, Long Island,
 N. Y., a corporation of New York

Application June 11, 1946, Serial No. 675,947

4 Claims. (Cl. 40—125)

1

This invention relates to a sign stand; more particularly to a stand and frame for displaying posters, billboard material or the like.

It is an object of my invention to provide a sign stand whereby sheeting such as paper bearing advertising matter, posters or billboard material may be displayed out of doors, such as the sidewalk portion adjacent localities where gasoline products are vended, and to provide a stand whereby poster material, either light weight cardboard, paper and the like, may be held in position in a neat and tautened condition, and rapid change may be effected without requiring the skill of a billboard paper hanger, and the attendant pasting operation in applying billboard material.

More particularly, my invention has for its object the provision of a sign stand whereby billboard material, poster paper or the like may be held in the frame of a sign stand mechanically, and to have the sign resist the stresses encountered by exposure to the weather, without the necessity for unduly weighting the stand or going through the laborious operation of pasting such billboard, poster paper or the like in position. It is contemplated by my invention to provide a sign stand in which a frame element is yieldably supported to swing in the wind and restore itself to normal position, whereby it may perform its function for advertising purposes without the necessity for anchoring or unduly weighting the stand.

Still further objects of my invention reside in the provision of a sign stand which may be shipped in a knock-down condition, and which is readily installed and "set-up" by the use of simple tools to a rigid condition, while involving low cost manufacturing and assembly operations.

To attain these objects and such further objects as may appear herein or be hereinafter pointed out, I make reference to the accompanying drawing forming a part hereof, in which—

Figure 1 is a perspective view showing my sign stand;

Figure 2 is a magnified fragmentary section taken on the line 2—2 of Figure 1;

Figure 3 is a fragmentary magnified side elevation taken on the line 3—3 of Figure 2;

Figure 4 is a front elevation of the sign stand;

Figure 5 is a fragmentary magnified sectional view taken on the line 5—5 of Figure 4;

Figure 6 is a fragmentary perspective view of the frame of the stand, with the parts thereof opened to show the operation thereof;

Figure 7 is a perspective exploded view of the base and upright, with some of the parts thereof

2

sectionalized, to show the method of assembly thereof.

Making reference to the drawing, there is shown a sign stand 10 comprising base members 14, supporting spaced uprights 12—12, between which a frame member 13 is supported. It is contemplated by me to employ bent sheet metal to secure lightness of weight, without sacrificing rigidity, whereby the webs and flanges of these members are nested to facilitate assembly and add strength and rigidity.

In accordance with this concept, the base members 14 constitute webs 14, having side branches 15, to provide spaced feet 16. A peripheral flange 17 extended from the body thereof rigidifies the webs 14 and merges medially into an extension 18, from which is stamped or cut the upwardly directed bracing tongue 19, to provide a slot 20. The resultant construction provides a loop arranged to receive the upright 12 comprising a channel defined by the web 21 and the side flanges 22—22, terminating into a rectangular end 23. The opposite end of the upright 12 is tapered at 24 and is capped with a plate 25 by welding. A boring 26 provides a bearing for the trunnion 27, supporting the flange 13, as will be described in greater detail hereafter.

A cross bar 28 is generally of U-shaped channel construction and has its opposite ends 29 provided with end plates 30, each of which is preferably welded to the cross bar 28 in butt-joint engagement with an end 29 thereof.

The webs 14 and 21 and the plates 30 are each formed with pairs of drill holes 31, 32 and 33, respectively, each pair equally spaced so as to be aligned when the webs, uprights and cross bar are assembled as hereafter described.

With the parts so provided, the upright 12 is slid into the loop 20. The plates 30 are designed to nest snugly between the flanges 22—22 of the upright 12. In this position the drill holes 31, 32 and 33 are in alignment and have had passed therethrough the bolts 34. The shanks of these bolts have applied thereto the nuts 35, to hold the uprights loosely in position.

The frame member 13, previously mentioned, is constituted of formed angles 36, 37, whose branches 38, 39 peripherally outline the illustrated rectangular frame by mitering. The branches 40 and 41 are arranged contiguously, sandwiching a backing plate 42, and in this position are welded, riveted or otherwise connected to each other.

The branches 40 and 41 inwardly terminate into semicircular segments 43 and 44, providing

more or less a cylindrical bead 45 which bulges symmetrically to opposite sides of the backing plate 42. A strap 46 is welded or otherwise attached to the peripheral edges of the branches 38 and 39 of the angle irons 36 and 37. A substantially U-shaped strap 47, having branches 48 and 49, is attached to the upper peripheral edge of the strap 46 encircling the frame thus far described.

Each of the branches 48 and 49 carries a trunnion 21, previously described, aligned in opposed relationship, each to enter a bearing 26 provided in the uprights 12. The trunnions 21 are positioned nearer the upper edge of the frame 13 than the center to weight the frame in a vertical position, however permitting easy pivotal movement about the trunnions 21 in the bearings 26 afford no greater resistance to a gust of wind. After each trunnion 21 is inserted in the respective bearing 26, the nuts 35 are tightened on the bolts rigidly, to bind the uprights 12 to the base members 11.

The bottom of the external frame 13 is provided with corner straps 47, welded or otherwise attached to the peripheral strap 46.

To the strap 47 there is affixed a pair of U-shaped straps 51, whose upright branches 52—52 terminate in offset sections 53, 53, to provide stops for the internal locking frames 54. These frames 54 are formed of angle members 55, having flanges 56 arranged to nest in parallelism with the branches 38, 39 of the external frame 13. Inwardly directed branches 57 terminate in substantially semi-circular ridge portions 58, contoured substantially concentric to the beads 43, 44, previously described. The locking frames 54 are of a size and configuration conforming to the outer main frame defined by the angle irons 36, and 37, to be nested therein and to receive within the ridge portion 58 the beaded portion formed by the loops 43 and 44.

The locking frames 54 may each sandwich a billboard sheet or poster sheet 59, and when brought together, wedge the terminal portions 60 between the ridges 58 and the beads formed by the portions 43 and 44. Tensioning of the frames 54, 54 toward each other against the backing plate 42 serves to tauten the billboard paper or poster 59 against the backing plate 42.

To maintain the aforesaid tautened positioned resilient fasteners 61 are employed. I have found it desirable to use a form of cowl fastener including a shank 62, which may pass through aligned drill holes in the flanges 40, 41 and the branches 57 of the locking frame 54. In the illustration six such cowl fasteners are illustrated. In the form illustrated the shank of each of the cowl fasteners is revolutely anchored in one frame, such as the branch 57, with the locking end 62 having the camming slot 63 arranged to engage the cross spring member 64, the ends of which are permanently affixed diametrically across the drill holes previously mentioned on the opposite branch 57 of the locking frame. A cowl fastener known under the tradename "Dzus" has been found suitable for my purposes, though it will be understood that other resilient tensioning fasteners may be employed by me.

It will be observed that by my device, the outer or external frame defined by the backing plate 42 and the beaded flanges 43 and 44, coupled with the inner locking frames 54 carrying the ridges 58, billboard material 59 in the form of paper, posters or the like may be tautened against the backing 42. By the provision of resilient fasten-

ing elements, the interengaging beads stretch the sheeted material 59 in smooth and drum-tight tension, without the application of paste to the backing plate 42. Vendors servicing these signs need only unfasten the resilient fastening element 61 which permit the frames 54 to pivot as shown in Figure 6, to the point where they rest against the stops 52. In this position, the flexible sheet 59 may be centered, and as one of the frames 54 is moved to the nesting position, progressively pinching the sheet 54 first at the bottom edge by the use of the stops 52 and then at the side and top edges. The operator in holding the two opposed frames against the backing plate 42 may thereupon adjust the fasteners 61 with the desired resilient tension, to hold the frame in assembled relationship.

Flexibility is afforded to the frame assembly 13, which is pivoted by the trunnions 21 on the upright 12. Free and easy swinging movement is afforded by the off-center suspension of the frame assembly 13. Thus, rigid anchoring of the entire sign assembly or weighting the same in position for all practical purposes is unnecessary as the frame assembly 13 will respond to any puff of wind and yieldingly swing with it rather than upset the sign assembly. As the wind dies down, the frame swings back to the normal vertical position.

In this way I have provided an exterior sign stand which may be readily shipped in knocked-down condition and quickly assembled, and provided in the assembled position the rigidity requisite for its intended purpose.

Having thus described my invention and illustrated its use, what I claim as new and desire to secure by Letters Patent, is:

1. In a sign, a frame assembly for displaying and mechanically holding on opposite faces thereof sheets of paper having advertising matter comprising an external frame element formed of a pair of symmetrical frame elements, each frame element being formed of angle sections, one branch of said angle sections forming the periphery of the frame element, the other branch being inwardly directed contiguous to the cooperating frame element and united thereto, holding therebetween a backing plate, symmetrical locking plates, each nested within the frame defined by the first pair of frame elements and resilient locking means engaging said inwardly directed branches, said locking frames comprising angular sectional elements, one branch of which is arranged to lie in parallelism with the peripheral branch of the first frame element, the other branch of said locking frame section including a locking head cooperating with said first frame element to tauten the sheeting material against the backing plate.
2. In a sign frame assembly for mechanically holding on opposite faces thereof sheets of paper having advertising matter or the like, comprising an external frame element formed of a pair of symmetrical frame elements, each of which elements is formed of angle sections substantially at right angles having the branches thereof substantially at right angles to each other, one branch forming the periphery of the frame, and the other being inwardly directed, a backing plate between said frames joined to said inwardly directed branches of said frames, a beaded segment formed on said inwardly directed branches, symmetrical locking plates, each formed of angle sections, the branches whereof are substantially at right angles to each other, one branch where-

of being inwardly directed, with the terminal edges beaded and complementary to the beaded sections of said first angle sections whereby said beaded sections may be brought in nesting position, resilient fastening means for joining said frame sections to nest said beaded sections about the edges of said sheets of paper to tauten the same with relation to said backing plate, means for pivoting said nested sections including abutment members adjacent one edge of said frame assembly whereby the sheets of paper may be progressively pinched in position between complementarily nested elements.

3. In a sign stand having a frame assembly for holding on opposite faces thereof sheets of poster material, in which said frame has trunnion elements extending from each side thereof and uprights having bearing portions within which said trunnions are journaled, said uprights comprising sheet metal formed into channel members, a pedestal assembly for said uprights comprising base members formed of sheet metal comprising a web member, peripheral flanges extended laterally therefrom defining a loop at a medial portion to receive the base of one of said uprights, a cross member having end plates each of which is nested within the channel of one of said uprights whereby said web of said base, the uprights and the end plates are stacked in face-

to-face contact, and tie members to hold said stacked elements together.

4. In a sign stand having a frame assembly and uprights of channel sections and trunnion elements extended from said frame assembly journaled in said uprights, the combination therewith of a pedestal assembly for said uprights comprising a pair of base elements and a cross member, said base elements being formed of sheet metal having a web portion and peripherally extended lateral flanges, the medial portion of which defines a loop to receive the base of one of said uprights, the channel portion of said uprights being arranged to receive an end plate extended from said cross bar in nested position therewith, and tie members to join said web of said base material, an upright and an end plate.
